UNITED STATES PATENT OFFICE.

EUGENE H. BENOIST, OF ST. LOUIS, MISSOURI.

WINDOW-REFRIGERATOR.

SPECIFICATION forming part of Letters Patent No. 275,799, dated April 17, 1883.

Application filed December 19, 1882. (No model.)

To all whom it may concern:

Be it known that I, EUGENE H. BENOIST, of St. Louis, Missouri, have made a new and useful Improvement in Window-Refrigerators, 5 of which the following is a full, clear, and exact description, reference being had to the annexed drawings, making part of this specification, in which—

Figure 1 is a view in perspective, showing 10 the improvement in position; and Fig. 2, a vertical transverse section.

The same letters of reference denote the same parts.

The present improvement is used in connection 15 with the window of a building, the invention consisting in a receptacle for provisions or any articles that are ordinarily placed in a refrigerator, which is attached to a building on the outer side of the window, the window- 20 sash forming the door to the refrigerator.

A, Figs. 1 and 2, represents a desirable form 25 of the refrigerator. The top a is preferably curved, extending from the window-sash B outward and downward to the bottom a' of the construction. The bottom a' may rest upon the window-sill C. The ends a^2 serve to complete the inclosure.

The refrigerator is held in place conveniently by fastening the ears a^3 to the sides 30 D D of the window E; or it may be screwed to the sides D D, as shown in Fig. 2.

The refrigerator should be so adapted to the window as not to interfere with the usual movements of the window-sash.

35 A flexible lip, a^4 , is preferably used at the top of the refrigerator to fit against the window-sash for the purpose of forming a joint with

the window-sash, and so that the sash can be freely moved upward and downward. The construction is perforated at various places, 40 a^5 a^6 , to provide for the admission of the outer air. The top a is preferably extended, as shown, to fit as accurately as is practicable to the window-frame. The extensions a^7 of the top also serve to protect the apertures a^6 from 45 the weather.

As shown in the drawings, the refrigerator A is made in length equal to the full width of the window. This is not in all cases essential. The refrigerator may be made shorter 50 than the width of the window; but in such case the refrigerator should be attached at one end to the window-frame D. The end a^2 is made to fit as closely as is practicable to the window-sash, and substantially as shown in 55 Fig. 2.

The interior of the refrigerator may be provided with shelves, or otherwise constructed suitably for the reception of the articles to be refrigerated. The interior of the receptacle 60 is reached by raising the window-sash.

I claim—

1. The receptacle A, perforated in the bottom and in the ends, and having its top a extended over the ends, substantially as described.

2. The combination of the receptacle A, perforated at various points for the admission of the outer air, the lip a^4 , the window E, and the sash B, substantially as described.

EUGENE H. BENOIST.
